[57] **ABSTRACT**

This invention is directed to the production, by synthesis, of tertiary aliphatic amines by amination of alkyl haloids, by means of secondary aliphatic amine, wherein a reaction mixture is prepared which consists of two fractions, one fraction comprising at least one alkyl haloid consisting mainly of halogen-1-alkane, the other fraction consisting of a secondary aliphatic amine within an aprotic dipolar solvent capable of dissolving the halide and the secondary amine but not of appreciably dissolving in the cold state the resulting tertiary aliphatic amine, whereby operation at relatively low temperatures and pressure values can be performed.

METHOD OF SYNTHETIZING TERTIARY
ALIPHATIC AMINES BY AMINATION OF ALKYL
HALIDES

The present invention relates to the production by synthesis of tertiary aliphatic amines by amination of alkyl halides.

The following methods of synthetizing tertiary amines are already known:

a. Action of formol and formic acid on a fatty primary amine (Eschweiler Clarke's reaction). In this process, hydrogen may be substituted for formic acid.

Apparently, this reaction has a complicated mechanism and the maximum observed yield is about 80 percent.

b. Action of formol and hydrogen on fatty nitrile.

This reaction starts at a preparation step antecedent to the one resulting from the above-mentioned process (a), in that the initial material is nitrile in lieu of amine. The yield is of the same order of magnitude as that of method (a).

c. Action of dimethylamine on a fatty alcohol.

This reaction takes place under a relatively high pressure of the order of 200 to 300 bars (2,900 to 4,350 psi).

d. Action of a dialkylamine and notably dimethylamine on an alkyl halide.

This reaction has also been known for a long time and may be written in the form:

wherein R designates an alkyl, X a halide, R' and R'' low-molecular weight alkyl radicals such as methyl, ethyl, propyl, etc.

As a rule, this reaction takes place in an aqueous medium at temperatures within the range of 50° to 190° C. The pressure normally reached during the reaction is generally of the order of 40 to 50 bars (580 to 725 psi) and may sometimes exceed 80 bars (1,160 psi). This reaction is complete and rapid only if a considerable excess of dialkylamine of the order of 12 to 18 moles per mole of alkyl haloid is used.

If the dialkylamine molar excess is only of the order of 2 to 3 moles per moles of halide, the reaction time requires generally more than 3 hours, thus impairing the economy of the process and the final quality of the resulting tertiary aliphatic amine.

From this last-named process, the present invention aims at avoiding the inconveniences set forth hereinabove which reside chiefly in the use of relatively high temperatures and pressures during a considerable time period.

With the method of this invention for the production of tertiary aliphatic amines by amination of an alkyl halide by using a secondary aliphatic amine is characterized in that a reaction mixture is prepared which comprises two fractions, the first fraction consisting of at least one alkyl haloid and comprising a major part of halogen-1-alkane, the other fraction consisting of a secondary aliphatic amine within an aprotic dipolar solvent capable of dissolving both the halide and the secondary amine but not capable of appreciably dissolving, in the cold state, the resulting tertiary aliphatic amine.

In fact, it was observed that aprotic dipolar solvents are capable of dissolving at the same time considerable amounts of alkyl halides and secondary amines as used for the synthesis of tertiary amines, without appreciably dissolving these last-named amines in the cold state. Therefore, the reaction takes place in a homogeneous medium, in contrast with most of the other processes mentioned hereinabove.

It has been found that as a result of the practical application of this method the use of this type of solvent will increase considerably the amination reaction rate and therefore permit of operating at considerably lower temperature and pressure values than in said prior art methods.

Moreover, as it is not soluble in the medium the tertiary amine resulting from the reaction can be extracted or recovered by using a simple physical step consisting, for example, of a decantation which can then be followed by a distillation.

According to this invention, the halide is halogen-alkane obtained by hydro-halogenation of alpha-olefines, according to a radical or so-called "abnormal" reaction. It comprises as a rule four to 22 carbon atoms and preferably eight to 18 carbon atoms. Also preferably, bromo-alkanes consisting of a major part of bromo-1-alkane will be selected. However, bromides may be replaced by chlorides. Nevertheless, it should be born in mind that it is much more difficult to obtain chloro-1-alkane of adequate grade from starting materials of petroleum origin.

Said first fraction of the reaction mixture advantageously contains at least 85 percent by weight of halogen-1-alkane.

The secondary amines used in the process of this invention correspond to the general formula:

wherein R' and R'' are saturated or unsaturated alkyl radicals containing one to 18 carbon atoms and preferably one to four carbon atoms.

These secondary amines are symmetric or asymmetric. They consist preferably of dimethylamine, diethylamine, diallylamine, dipropylamine and diethanolamine.

A molar ratio of 2 moles of secondary dialkylamine per mole of alkyl bromide (or chloride) is used, this excess being sufficient for fixing the hydrobromic (or hydrochloric) acid released during the reaction:

The above-mentioned aprotic dipolar solvents suitable for use in the method of this invention are those having the property of dissolving considerable quantities of secondary amines and alkyl halides without appreciably dissolving tertiary amines (in the cold state) as produced during the reaction, said solvents consisting preferably of dimethylformamide, hexamethylphosphorotriamide, tetrahydrofuran and N-methylpyrrolidone.

The proportion of solvent utilized ranges advantageously from 0.6 to 2 parts by weight of the halide. Different proportions of solvents may be used without departing from the scope of the invention.

The crude tertiary amine thus obtained is free of alkyl halide and its degree of purity is generally in excess of 90 percent by weight; the product is colourless and a simple removal of the first fraction of the product by distillation yields an amine having a degree of purity in excess of 98 percent.

It may also be noted that no quaternary ammonium is released or formed during the reaction.

Finally, the reaction is carried out under a pressure above the atmospheric value but below 4 bars (58 psi).

Various modes of embodying the method of this invention are described hereinafter by way of example. In these examples the fractions, portions and percentages are given by weight.

Example 1

In a reactor capable of withstanding a pressure of about 2 bars (30 psi) a solution of 360 parts of dimethylamine in 1,200 parts of dimethylformamide is reacted with 1,100 parts of bromo-1-tetradecane prepared by hydrobromidizing tetradecene-1. Within 15 minutes the temperature rises spontaneously to 80° C. Then the temperature is raised to 150° C during 45 minutes, the pressure remaining equal or inferior to 1 bar (14.5 psi) during this period, and then the reagents are allowed to cool to room temperature. The reaction mixture separates spontaneously into two layers. After removal of the lower or bottom layer, 993 parts of a clear, colourless product are collected which contain 90.2 % by weight N-dimethyltetradecylamine, 9 % b.w. hydrocarbons and 0.5 % by weight dimethylamine. This product is free of unreacted bromoalkane, quaternary ammonium salts and hydrobromic acid, and can be purified very easily by simply removing the head under reduced pressure, thus yielding N-dimethyltetradecylamine having a degree of purity in excess of 98 % by weight.

Example 2

In a process similar to that described in example 1, hexamethylphosphorotriamide was substituted for dimethylformamide in the same proportions. From the same amounts of dimethylamine and tetradecyl bromide, and after removing the bottom layer, 990 parts of crude amine containing 89.7 % by weight N-dimethyltetradecylamine, 0.6 % dimethylamine and 9.1 % by weight hydrocarbon were collected.

Example 3

In a reactor capable of withstanding a pressure of about 2 bars (30 psi) a mixture consisting of 1,100 parts of tetradecyl bromide containing 95 % by weight bromo-1-tetradecane and 1,180 parts of a 32 % b.w. dimethylamine solution in N-methylpyrrolidone is stirred. The temperature rises spontaneously to 80° C, the pressure within the reactor rising likewise to about 0.5 bar (7.25 psi); the stirring is discontinued and the mix allowed to cool to room temperature; then, after removing the bottom layer separating spontaneously by decantation, a clear, colourless product containing 76.6 % by weight of N-dimethyltetradecylamine, 1 % b.w. of dimethylamine, 8.1 % by weight of hydrocarbons and 6.1 % b.w. of tetradecyl bromide is obtained.

Example 4

In a process similar to the one described in Example 1 and by utilizing n-decyl bromide and dimethylamine dissolved in dimethylformamide, the reagents being used in the same molar proportions as in Example 1, a clear, colourless product was separated by decantation and after removal of the head under reduced pressure this product gave substantially pure N-

dimethyldecylamine with a 86 % yield with respect to alkyl bromide.

Example 5

In a flask equipped with an agitator 97 g (1 mole) of 5 diallylamine, 100 g of dimethylformamide and 138.5 g (0.5 mole) of tetradecyl bromide are introduced. The mix is heated during 2 hours, while stirring, to 150° C; the previously homogeneous reaction mixture thus separates into two fractions. These fractions are allowed to 10 cool to room temperature and the stirring is discontinued. The upper layer consisting mostly of N-diallyltetradecylamine was subjected to a fractional distillation under reduced pressure and yielded a high percentage of N-diallyltetradecylamine having a high degree of purity.

15

In the preceding examples the alkyl haloid utilized was bromide. Advantageous results may also be obtained from chlorides as shown by the following example 6.

20 Example 6

In a reactor capable of withstanding a pressure of about 2 bars (30 psi) a mixture consisting on the one hand of 1,100 parts of a dodecyl chloride containing 93 % by weight of chloro-1-dodecane manufactured by 25 chlorinating dodecyl alcohol, and on the other hand of 1,120 parts of a 40 % solution of dimethylamine in dimethylformamide was stirred. The temperature increased to 150° C, so that the pressure in the reactor attained 0.7 bars (11.15 psi). The stirring was discontinued and the liquid is allowed to cool to room temperature.

30 After decantation and removal of the bottom layer, a clear, colourless product was obtained which, after removing the head, yielded N-dimethyldodecylamine having a degree of purity in excess of 98 % by weight, with a yield of 88 % in comparison with alkyl chloride.

The method and its various forms of embodiment disclosed hereinabove are adequate for a batchwise production of tertiary amines. Now, it was also attempted 40 to take advantage of the relatively easy separation of the reaction product for performing a continuous reaction process.

However, it was found that as the reaction proceeds the increment in the secondary amine halohydrate

45

50 is attended by a substantial reduction in the quantity of unreacted alkyl haloid and of the resultant tertiary amine, so that these two compounds have a natural tendency to become jointly separated from the reaction medium, the halide becoming soluble in the tertiary amine. As a result, a strong agitation is necessary for 55 completing the reaction, the latter taking place in a heterogenous phase and leading to an undesirable percentage of quaternary ammonium halide.

Now it was discovered that this inconvenience could 60 be removed by compensating the reduction in solubility of alkyl halide and tertiary amine by gradually increasing the temperature during the reaction.

On the other hand, it was also found that the quantity 65 of solvent utilized must be such that all the products and subproducts of the reaction remain in solution throughout the reaction time; as a result, the product obtained by cooling and decantation consists nearly wholly of the formed aliphatic tertiary amine. This re-

sult is obtained when the ratio, by weight, of solvent utilized to the alkyl halide input ranges from 2:1 to 5:1.

This invention is also applicable to a method permitting of producing tertiary amine as a continuous process, this method being characterized in that the reaction mixture is circulated and exposed during its circulation to a gradually increasing temperature and that the ratio of solvent to the alkyl halide ranges from 2:1 to 5:1 by weight, the reaction product being subsequently cooled and then decanted in a continuously operating decanting vessel.

Thus, the reduction in the solubility of the formed tertiary amine and of the unreacted alkyl halide as a function of the increment in the secondary amine halohydrate concentration is compensated as the reaction proceeds by the increase in solubility due to the gradual temperature increment and, on the other hand, the vapour pressure increment of the secondary amine, as a consequence of the reduction in the solubility of this amine when the temperature increases, is compensated by the amine consumption as the reaction proceeds, due to the very temperature increment.

Under the thus established reaction conditions, the crude tertiary amine separating spontaneously from the reaction mixture is free of alkyl haloid, quaternary ammonium salt and secondary amine halohydrate. Moreover, its coloration is inferior to 1 Gardner (according to the US Standard ASTM D255, Gardner Color Standards, 1953).

Moreover, the pressure may be kept at a value below 2 bars (about 30 psi) so that the necessary apparatus is simplified with the additional advantageous feature that the process may be carried out in a suitable glass or plastic apparatus, so that pollutions by metal salts can safely be avoided.

By way of example, the continuous manufacturing method of this invention may be carried out in an apparatus of the type illustrated diagrammatically in the single FIGURE of the attached drawing.

This apparatus comprises a reactor 1 consisting of a vertical column 2 of borosilicate glass having a height of about 13 ft. and a diameter of 4 inches. This column 2 is provided with a plurality of heating elements 3 such as coil tubes or the like disposed at spaced intervals along the longitudinal axis of the column and supplied with heating fluid at different temperatures so that the temperature within the reaction column 2 increases from bottom to top. Advantageously, the column 2 contains filling bodies (not shown) such as Rashig rings. This column 2 is fed from the bottom whereby alkyl bromide is supplied through a conduit 4, dimethylformamide through another conduit 5 and dimethylamine through a branch conduit 6 leading into conduit 5, as shown.

A complementary conduit 7 leads from the top of column 2 down into a cooling device 8 consisting of

surface-type heat exchanger through which a suitable cooling fluid is circulated, and opens into a decanter 9.

This decanter 9 consists of a closed vessel provided at its upper portion with a pipe 10 for exhausting the excess dimethylamine in the gaseous state, a lateral outlet pipe 11 leading from the upper portion of the decanter for recovering the crude tertiary amine formed in the liquid state, and, at the bottom, another pipe 12 bent to an "S" shape (turned about 90° in its plane) for discharging the bottom solution of dimethylamine hydrobromide in dimethylformamide. A small vertical tube 13 opening into the atmosphere extends from an upper point of this pipe 12 to prevent the latter from acting as a siphon.

The conventional accessories inherent to chemical apparatus of this character, such as supports, brackets, pumps, metering devices valves and sundry brass-founding articles, as well as measuring and regulating instruments, are not shown as their type, position and arrangement will readily occur to those conversant with the art.

For implementing the above-described apparatus the heating elements 3 are operated for heating the column 2 with a temperature gradient comprising regular steps increasing from bottom to top from 20° to 150° C.

The alkyl bromide and secondary amine in solution in the solvent are introduced into the bottom portion of column 2 via conduits 4, 5 and 6, the outputs being adjusted by means of suitable metering pumps (not shown). The reaction mixture is taken from the top of the column and directed through the cooler 8 to the continuously operating decanter 9 where the amine is recovered in the upper phase with a degree of purity approximating 90 %, the impurities being ascribable chiefly to the initial materials.

The rate of feed of the raw materials corresponds to a reaction time of 4 to 15 minutes.

The molar ratios of secondary amine to alkyl halide are within the range of 2:1 to 4:1.

The amounts of solvent utilized are by weight in the proportion of 2:1 to 5:1 by weight of the alkyl halide input.

Although the secondary amine excess to be used in this process is relatively low, its reaction rate is relatively high.

As they emerge from the conduits 12 and 10, the reaction by-products as well as the solvent are recovered and recycled by using any known and suitable means not within the scope of this invention.

The following table gives the numerical data concerning eight tests of continuous tertiary amine production according to the method of this invention, the solvent consisting in all cases of dimethylformamide, and the secondary amine consisting of dimethylamine.

TABLE

Test No.	No. of alkyl radical carbon atoms	Bromo-1-alkane (% b.w.)	Alkyl bromide output (kg/hr)	Dimethyl-amine to alkyl bromide molar ratio	Dimethyl-formamide to alkyl bromide molar ratio	Temp. (°C)	Crude amine output (kg/hr)	Percent composition of crude tert. amine			
								Amine	Alkyl brom.	Quatern. ammonium salts	Yield (%)
1	14	92	15	3/1	2, 2/1	20 à 120	13	85, 6	2, 8		0 90
2	14	92	15	4/1	3, 8/1	20 à 140	12, 15	88, 7	0		0 95
3	14	91, 2	15	2, 1/1	2, 2/1	20 à 140	13, 1	88, 2	traces		0 94
4	14	91, 2	15	2, 1/1	4, 3/1	20 à 140	12, 9	88, 8	0		0 94

TABLE - Continued

Test No.	No. of alkyl radical carbon atoms	Bromo-1-alkane (% b.w.)	Alkyl bromide output (kg/hr)	Dimethylamine to alkyl bromide molar ratio	Dimethylformamide to alkyl bromide molar ratio	Temp. (°C)	Crude amine output (kg/hr)	Percent composition of crude tert. amine		
								Amine	Alkyl brom.	Quatern. ammonium salts
5	14	92.6	15	2.3/1	3.25/1	20 $\ddot{\text{A}}$ 120	13.05	86.3	1.4	0 91
6	18	88	10	3.2/1	3/1	20 $\ddot{\text{A}}$ 140	8.65	87.6	0	0 94.8
7	10	94.4	15	2.9/1	3/1	20 $\ddot{\text{A}}$ 140	12.6	88.1	0	0 94.2
8	12	93.4	15	3/1	3/1	20 $\ddot{\text{A}}$ 140	13	88.0	0	0 95.1

The yield mentioned in this table was calculated as follows:

$$P \times 100/p$$

wherein P denotes the total weight of pure tertiary amine contained in the resultant crude amine, and p the weight of amine to be theoretically obtained from the bromo-1-alkane contained in the crude alkyl bromide utilized.

What is claimed as new is:

1. A process for the continuous production of aliphatic tertiary amines comprising circulating together in a reactor at least one alkyl halide consisting essentially of halo-1-alkane, at least one aliphatic secondary amine and at least one anhydrous organic solvent adapted to dissolve the raw materials and the byproducts of the reaction and not appreciably dissolve in the cold state the resulting aliphatic tertiary amine, said solvent being selected from the group of dipolar aprotic solvents comprising dimethyl formamide, hexamethyl phosphorotriamide, tetrahydrofuran and N-methylpyrrolidone, heating the mixture of said materials to a temperature of about 150° C, passing said mixture through a cooler and into a separator in which the resulting liquid separates into two layers, and collecting from the top layer the liquid aliphatic tertiary amine which has been produced.

2. A process according to claim 1, wherein said alkyl halide is a halo-1-alkane produced by hydrohalogenation of olefins according to a radical reaction.
3. A process according to claim 1, wherein the alkyl halide contains at least 85% by weight of halo-1-alkane.
4. A process according to claim 1, wherein said alkyl halide is selected from the group consisting of the alkyl bromides and chlorides containing eight-22 atoms of carbon.
5. A process according to claim 1, wherein each of the alkyl radicals of the secondary amine contains one-18 atoms of carbon.
6. A process according to claim 1, wherein the quantity of solvent in relation to the alkyl halide is in the proportion of 2/1 to 5/1 by weight.
7. A process according to claim 1, wherein the proportion of secondary amine and alkyl halide is such that there is a molar ratio of at least two molecules of secondary amine to one molecule of alkyl halide.
8. A process according to claim 1, wherein the secondary amine is introduced into the reactor after having been mixed with the solvent.
9. A process according to claim 1, wherein the mixture is heated to a temperature which increases as the mixture flows through the reactor.
10. A process according to claim 1, wherein the reaction is carried out at a pressure higher than atmospheric pressure and less than 4 bars.
11. A process according to claim 1, wherein the reaction mixture is kept at a pressure below 2 bars while it is subjected to a progressively increasing temperature.
